[57] **CLAIM**

The ornamental design for a razor, as shown and described.

DESCRIPTION

FIG. 1 is a rear perspective view of a razor showing my new design;

FIG. 2 is a rear elevational view thereof;

FIG. 3 is a front elevational view thereof;

FIG. 4 is a right side elevational view thereof, the side opposite being a mirror image of the side shown;

FIG. 5 is a top plan view thereof; and,

FIG. 6 is a bottom plan view thereof.

The broken lines showing the razor blade, portions of a razor blade and outlines on the handle surfaces are for illustrative purposes only and form no part of the claimed design.

The surface(s) or portion(s) of the article not shown in the drawing or described in the specification form(s) no part of the claimed design.
